UNITED STATES PATENT OFFICE.

PHILIP JOFFE, OF NEW YORK, N. Y.

MUSIC-SHEET.

1,331,993.

Specification of Letters Patent. Patented Feb. 24, 1920.

Application filed August 24, 1918. Serial No. 251,256.

To all whom it may concern:

Be it known that I, PHILIP JOFFE, a citizen of the United States, residing at 919 Second avenue, borough of Manhattan, city 5 of New York, in the county of New York and State of New York, have invented certain new and useful Improvements in Music-Sheets, of which the following is a specification.

10 My invention relates to music sheets and has for its object to provide the sheets with means adapted to facilitate the turning thereof.

As practically all musical instruments are 15 played with both hands, it is difficult to turn the sheets of music from which the performer is playing, with sufficient certainty and rapidity to avoid interruption of the performance. In many cases an attendant 20 is required to turn the sheets of music for the performer. Large numbers of sheet turning machines have been devised and patented. Many unfortunate accidents have occurred at important concerts due to the 25 turning over of more than one sheet at a time or failure to turn the sheet at the requisite time to avoid interruption of the performance. Musicians have recognized this difficulty for years, but no safe and sat- 30 isfactory means ever has been found to overcome the difficulty.

It is the purpose of my invention to obviate this difficulty by a simple, inexpensive 35 construction which enables the sheets to be turned by either hand with rapidity and certainty and which obviates the danger of turning more than one sheet at a time. My invention is capable of many embodiments and many similar uses and I have chosen 40 the particular embodiment disclosed merely for purposes of illustration and without any intent to limit its scope or applicability.

The single figure of the drawing shows an embodiment of my invention applied to 45 sheet music.

It is the purpose of my invention to provide each sheet with a part which protrudes or extends beyond a following sheet to a sufficient extent to enable the sheet to be 50 taken hold of singly and turned. In the embodiment of my invention chosen for pur-

poses of illustration, it will be noted that an edge of each sheet extends beyond the edge of the sheet which follows it. This extension may be provided throughout the entire 55 edge as illustrated, or may be confined to any desired portion or portions of one or more of the edges according to the specific problem presented. In the illustrated embodiment consisting of a piece of sheet music 60 having six sheets, it is convenient to cut or arrange each succeeding sheet so that a preceding sheet extends a sufficient distance beyond the edge of the succeeding sheet to enable the preceding sheet to be taken hold of 65 readily and with certainty. It is obvious that the invention may be carried out in this way or by the addition of parts capable of producing the desired result.

Many modifications of my invention will 70 be apparent to those skilled in the art without departing therefrom or from the scope of the claims, my invention consisting of means provided on each sheet so that a part of each sheet will extend beyond the next 75 succeeding sheet to facilitate and render certain the turning of each sheet.

Having described my invention what I claim and desire to secure by Letters Patent is:

1. A music book comprising a series of 80 sheets of gradually decreasing width, each of said sheets being narrower than the one preceding it, whereby each sheet can be turned over without disturbing the rest, the 85 difference of width between each sheet and the one following it being sufficiently great to permit each sheet to be taken hold of on both sides at its free edge independently of the following sheet. 90

2. A series of sheets of music assembled for consecutive use, each sheet having a part extending beyond a corresponding and less extending part on a plurality of adjacent subsequent sheets a distance sufficient to enable each said part to be taken hold of singly 95 without danger of grasping an adjacent subsequent sheet, whereby the necessary turning of single sheets during the use of said series is facilitated and rendered easy and 100 certain.

3. A series of sheets of music assembled

for consecutive use, each sheet having an integral and substantial part extending beyond each adjacent subsequent sheet a distance sufficient to enable each said part to be taken hold of singly without danger of grasping an adjacent subsequent sheet,

whereby the necessary turning of single sheets during the use of said series is facilitated and rendered easy and certain.

In testimony whereof I hereunto affix my signature.

PHILIP JOFFE.
